(57) **CLAIM**

We claim the ornamental design for footwear tightening reels, substantially as shown and described.

DESCRIPTION

FIG. 1 is a perspective view of footwear tightening reels showing my new design;

FIG. 2 is a top view thereof;

FIG. 3 is a left side view thereof;

FIG. 4 is a right side view thereof; and,

FIG. 5 is a front view thereof.

The broken lines shown in the drawings represent portions of the footwear tightening reels that form no part of the claimed design.
